(57) **CLAIM**

The ornamental design for a wall hanging bracket, as shown and described.

DESCRIPTION

FIG. 1 is an oblique view of a wall hanging bracket showing our new design;

FIG. 2 is a top view thereof;

FIG. 3 is a rear view thereof;

FIG. 4 is a right view thereof;

FIG. 5 is a left view thereof;

FIG. 6 is a bottom view thereof; and,

FIG. 7 is a front view thereof.

The dashed broken lines shown in the drawings depict portions of the wall hanging bracket that form no part of the claimed design.
